UNITED STATES PATENT OFFICE.

SHOZABURO KAWAI, OF NEW YORK, N. Y.

GAME.

Application filed August 30, 1924. Serial No. 735,214.

To all whom it may concern:

Be it known that I, SHOZABURO KAWAI, a subject of the Emperor of Japan, and a resident of the city, county, and State of New York, have invented a certain new and useful Game, of which the following is a specification.

The present invention relates to a game of the type in which a ball or marble is caused to travel over an inclined surface which is provided with means for deflecting the ball to cause it to take an irregular or tortuous path. One object of the present case is to provide a container or hopper in which the ball is deposited, ready to be released upon the inclined surface, the hopper having a transparent door or trap for releasing the ball, the latter being visible through the door prior to its release. The door is adapted to be operated by any individual player and for this purpose I provide a plurality of operating cords connected with common means for actuating the door so that any player may actuate the door and the operation will be the same even if a number of players simultaneously pull the operating cords. Another object of my invention is to provide an inclined surface or board on which the ball moves by gravity and is opposed or baffled by obstructions, such as pins, projecting from the board and after the ball moves down the inclined board the momentum carries it across the scoring board and thence upwardly at the opposite side of the scoring board onto an inclined and transparent shield. The ball is adapted to roll back and forth between this inclined, transparent screen, the scoring board and the inclined board on which it first travels, so that the ball takes the back and forth motion a number of times before settling down onto the scoring board. The latter is preferably provided with a row of shallow pockets or recesses for the ball to seat in and I prefer to divide the scoring board off into spaces suitably designated so that some lesser count may be given when the ball fails to be captured in one of the recesses or pockets.

In the drawing forming part of this application,

Figure 1 is a perspective view of a game embodying my invention, with part of the front shield broken away,

Figure 2 is a front elevation of the hopper from which the ball is released,

Figure 3 is a cross sectional view thereof,

Figure 4 is an enlarged sectional view showing the arrangement of the scoring board, and the adjacent inclined surfaces, and

Figure 5 is a longitudinal, sectional view through the scoring board.

The game device may be arranged for public playing at amusement parks, although it is not limited to this particular application.

In Figure 1 I have shown the game arranged adjacent a counter 1 which may be marked off as indicated at 2 with spacings and scoring indicators corresponding with the scoring indications on the scoring board but on a larger scale. The players may line up in front of the counter 1 and place coins on any of the spaces marked off at 2 so that the player who selects the space or pocket corresponding with the one on the counting board on which the ball finally comes to rest, will be the winner in any particular play.

There are arranged over the counter 1 in convenient position, to be grasped by the players, several pull strings 3, each engaging over a pulley 4 and united with a common operating cord 5, and I prefer to provide as many pull strings 3 as there are positions indicated by the markings 2 on the counter 1. Any individual player or any number of players may pull one or more of the strings 3 to release the ball and start the play. A common cord 5 passes over a pulley 6 and thence over a pulley 7 and its lower divided end 8 is connected with the opposite ends of a sliding trap 9 or door 9. The latter is slidable in front of the discharge opening 10 in a front wall of a hopper 11 which is provided with inclines 12 inside the hopper to deflect the ball to a position opposite the opening 10. The door 9 may be arranged to slide against a front wall 12a of the hopper and its upward movement is limited by the fixed stop 13 on this front wall, the movement being sufficient to permit the ball, deposited in the hopper, to roll out through the aperture 10 and over the member 14 onto the inclined board 15. The door 9 is made of transparent material, such as glass, in order that the players may observe the

position of the ball prior to its release from the hopper, so that the players will be influenced in selecting the spaces 2.

The ball released from the hopper first rolls down by gravity on the surface of the inclined board 15 striking against the pins 16 projecting from the surface of this board so that the ball is caused to take an irregular or tortuous path until it reaches the lower inclined board 17 which is substantially a continuation of the board 15, and it also has pins 18 for deflecting the ball in the same manner as the pins 16. The board 15 may be arranged in any desired angle with relation to the board 17 and this will be governed more or less by the height of the forward shield. As the ball rolls over the surface of the board 17 and is deflected by the pins 18, it moves onto the scoring board 19 which latter is preferably, though not necessarily, in a horizontal position. The top surface of this scoring board is preferably divided off by markings 20 and at regular intervals there are shallow recesses or pockets 21 in the surface of this scoring board in which the ball may come to rest. These pockets 21 are made shallow in order that the ball will not come to rest in one of them when the ball first moves down the board 17, but only after the ball has rolled back and forth in the manner hereinafter described.

At the forward side of the scoring board 19 there is a shield 22 of transparent material such as glass, and it is arranged at an obtuse angle in relation to the top surface of the board 19. As this shield is of transparent material the movements of the ball may be observed by the players at the front of the counter 1. When the ball is released from the hopper it moves down the board 15 being deflected by the pins 16 and it then moves down the board 17 being deflected by the pins 18; and it rolls across the scoring board 19 and upwardly on the shield 22; and from there it rolls back upon the board 19 and the board 17, sometimes striking the pins 18 on this return action. The ball may roll back and forth a number of times between the shield 22, the scoring board 19 and the board 17 and it may progress along these several members forwardly and backwardly so that the interest of all players is maintained until the ball finally comes to rest upon the scoring board 19, because of the uncertainty of the action of the ball in rolling back and forth upon the members 22, 19, 17.

Having described my invention, what I claim is:

1. A game comprising a scoring member on which a ball is adapted to come to rest, means forming an incline support on which

the ball is adapted to roll to said scoring member, and a second inclined support onto which the ball is adapted to roll after crossing said scoring member and before returning to and coming to rest upon said scoring member. 65
70

2. A game comprising a scoring member on which a ball is adapted to come to rest, means forming an inclined support on which the ball is adapted to roll to said scoring member, and a second, inclined support arranged on the opposite side of said scoring member to the said first inclined support, the ball being adapted to roll down said first inclined support, across said scoring member, upwardly on said second inclined support and back again on the scoring member to score. 75
80

3. A game comprising a scoring member on which a ball is adapted to come to rest, means forming an inclined support on which the ball is adapted to roll to said scoring member and a second, transparent, inclined support arranged on the opposite side of said scoring member to the said first inclined support, the ball being adapted to roll down said first inclined support, across said scoring member, upwardly on said second inclined support and back again on the scoring member to score. 85
90
95

4. A game comprising a scoring member on which a ball is adapted to come to rest, means forming an inclined support on which the ball is adapted to roll to said scoring member, baffle means on said inclined support to cause the ball to take an uncertain, irregular course thereover, and a second, inclined support arranged on the opposite side of said scoring member to said first inclined support, the ball being adapted to roll down said first inclined support, across said scoring member, upwardly on said second inclined support and back again on the scoring member to score. 100
105

5. A game comprising a scoring member on which a ball is adapted to come to rest, having recesses or pockets for the ball, means forming an inclined support on which the ball is adapted to roll to said scoring member, a second inclined support arranged on the opposite side of said scoring member to said first inclined support, the ball being adapted to roll down said first inclined support with sufficient momentum to pass over said recesses on the first crossing of said scoring member, the ball being adapted to roll upwardly on said second inclined support and thence back again to said scoring member to score. 110
